UNDERGROUND CONCRETE UTILITY VAULT

John B. Schack, Auburn, Wash., assignor to Concrete
Conduit Company, Auburn, Wash., a corporation of
Washington

Filed Apr. 27, 1967, Ser. No. 6,868

Term of patent 14 years

(Cl. D13—1)

FIG 1

FIG 2

FIG. 1 is a perspective view of the underground concrete utility vault showing my new design;

FIG. 2 is a top plan view thereof.

The design appearance of the vault is the same on all four sides.

I claim:

The ornamental design for an underground concrete utility vault, substantially as shown and described.
